ELECTRIC TRANSFORMER ESPECIALLY SUITABLE FOR USE IN CONNECTION WITH ELECTRIC FURNACES.

1,315,359.

Specification of Letters Patent.

Patented Sept. 9, 1919.

Application filed December 11, 1917. Serial No. 206,622.

To all whom it may concern:

Be it known that I, JAMES BIBBY, a subject of the King of Great Britain and Ireland, residing at London, England, have invented Improvements in or Relating to Electric Transformers Especially Suitable for Use in Connection with Electric Furnaces, of which the following is a specification.

With electric furnaces of the arc heating type it is necessary, with the larger sizes thereof, in order to distribute the source of heat over the bath of metal or other charge therein (hereinafter referred to as metal) and, at the same time to keep the electrodes within reasonable dimensions, to use four upper movable electrodes. These four electrodes are arranged generally vertically over the bath of metal and through them equal amounts of current flow to form arcs between their ends and the surface of the metal when the distance between the ends of the electrodes and the metal are equal, so that the resistances are equal. Consequently, it is necessary, when the source of electric supply is three-phase alternating current, to transform the three-phases into four equal phases in such a manner that when equal currents are being taken by the four arcs, equal currents will be taken from the three primary mains.

It is also important for metallurgical reasons that the four secondary currents should not be in equilibrium, that is to say, that the vector sum of the four currents should not be zero but that there should be a balance of current available for a common return fifth conductor and that this return current should, generally, to obtain the best results, be at least equal to that in one of the four phases, but may be less, though with reduced effect. This return current flows through a neutral fixed electrode in the hearth of the furnace so that the out of balance current, will flow in a more or less vertical direction through the bath of metal. The currents between the phases pass in a horizontal direction. When the vertical current equals or exceeds that in one of the four phases, metallurgical requirements will be satisfied.

Therefore to obtain the best results, a four phase current is required all the phases of which shall be equal to one another with respect to the neutral, and also a return neutral current that shall exceed or at least be equal to that of one of the phases, so that

there is obtained a four phase five wire system in which the conductors can be of similar sectional dimensions.

A four-phase current can be obtained from a three-phase current by a dual system of 60 Scott connections but this requires the equivalent of four transformers with six sets of connections on the high tension side, or, if only two transformers are used, the four phases are simply two sets of two phases in 65 parallel, which system has disadvantages.

The present invention has for its object to enable four equal phases to be obtained from three single phase transformers, or from one three-phase transformer, in such a manner 70 that the system shall be balanced to a permissible extent, on the three-phase primary side when equal currents are being taken in each of the four secondary phases and the before-mentioned common return current is 75 provided for; and also, that when the four phases become unequal through deficiency of electrode regulation, the currents in the three primary phases shall remain permissibly balanced.

For this purpose, in three phase transforming plant according to the present invention, the transformer ratio of two of the three single phase transformers, or of two of the associated sets of primary and secondary 85 windings of the single three phase transformer, may be made equal to one another and the transformer ratio of the third transformer or of the third set of associated primary and secondary windings of the single 90 transformer, be made of the order of about 20% greater value than that of the other two. If therefore the three primary windings of the three transformers or of the single three phase transformer are considered 95 for instance equal to one another in value, then of the three secondary windings of the three transformers, or of the single transformer, two of them are made equal to one another in value, and each of them is 100 connected at its ends separately by conductors to two of the four electrodes and the third secondary winding, under this condition of equal primaries is made of the order of about one-sixth less in value than 105 the other two, and is connected at each of its ends by a conductor to an intermediate point of one of the other two secondary windings and at its central point is provided with a tapping for connection through a fifth or a 110

return neutral conductor to the fifth electrode arranged in the hearth of the furnace. If on the other hand, the number of turns in all the secondary windings are considered equal in value to one another, then two of the primary windings will be made equal to one another and the third primary winding will be made of the order of about 20% greater in value than either of the other two, so as to satisfy the hereinbefore stated transformer ratio proportions. The number of turns in the respective windings and the points in the two equal secondary windings to which the ends of the third and it may be unequal winding are connected, are such as to enable the above described requirements to be obtained.

The primary windings in each case can be connected together either according to the star or delta method of connection.

In the accompanying illustrative drawings Figures 1 and 2 show, diagrammatically, transformer arrangements suitable for obtaining from a three phase transformer plant, four equal phases for use with four electrodes and a balance current for a return conductor and fifth electrode as hereinbefore described. These figures show the windings of either a single three phase transformer or three single phase transformers. Fig. 3 is a diagram herein-after more particularly referred to.

Referring to Figs. 1 and 2, the three primary windings AO, BO and CO are connected together at the point O according to the star method of connection and are, in this example, similar in value to one another, having the same number of coils or turns. VT, ZY and WX are the three secondary windings, two of which, namely WX and ZY are equal in value to one another, having the same number of coils or turns, while the other, namely VT, is of different and less value than the other two, having fewer coils or turns. Thus, windings WX and ZY should each have approximately 20% more coils or turns than the winding VT, that is to say, when the primary windings are equal to one another, the proportion of coils or turns in the windings WX and ZY to the coils or turns of winding VT may be about as 6 to 5 so that the transformer ratio of the windings AO, VT is about 20% greater value than that of the other two sets of windings BO, ZY and CO, WX. The opposite ends of the winding WX are adapted to be connected by conductors *a* and *b* to the two electrodes 1 and 2 respectively and the opposite ends of the winding ZY are connected by conductors *c* and *d* to the electrodes 4 and 3 respectively. The ends of the third secondary winding VT are connected to tappings at intermediate points L and K respectively on the other two secondary

windings WX and ZY. These intermediate points L and K are such as to divide the coils in these secondary windings into two portions in the proportions of the order of 7 to 17 as shown. At the middle point M of the third secondary winding VT is a tapping for connection by a conductor *e* to the neutral fixed electrode N in the hearth of a furnace, this conductor forming the common return neutral wire of the secondary system. When the windings are thus proportioned, arranged and connected up and the E. M. F.'s and currents indicated by the references E¹ and I¹ respectively in Fig. 2, in the primary windings are balanced, the E. M. F.'s between the electrodes 1, 2, 3 and 4 and the neutral electrode N will also be equal, as indicated by the references E², so that when the resistances between the four electrodes 1, 2, 3, and 4 and the fifth or neutral electrode N are equal, the currents which will flow between each of the four electrodes and the neutral electrode, will be equal, as indicated by the references I², and the required amount of current will flow back through the return conductor *e* between the neutral electrode N and the middle point M of the winding VT to satisfy the before-mentioned metallurgical requirements.

In the case where the secondary windings are made of equal value and the primary windings are made of unequal value, then the desired transformer ratio of one set of the windings to the other two sets should be of the order of six to five. Thus with an arrangement such as shown in Figs. 1 and 2 but under the modified conditions just mentioned the number of coils or turns in the primary winding AO would be 20% greater than in the windings BO and CO.

It can be readily shown that the hereinbefore described arrangement of transformer windings and electrodes fulfil all the required conditions hereinbefore mentioned.

For this purpose reference may be had to Figs. 1 and 2 and to Fig. 3, which is a clock diagram, and shows the system of connections when the star method is adopted for the primary windings. The arrangement is such that the transformer ratio of the set of windings AO VT is 20% greater than the transformer ratios of the sets of windings CO—WX and BO—ZY which are equal. In practice these transformer ratios may be obtained in any convenient manner. For example, if the secondary windings are all equal, then the number of turns or coils in the primary winding AO would as hereinbefore stated be about 20% greater than those in the primary windings BO and CO, but by way of example, it will be assumed that the transformer ratios are represented by the number of turns or coils in the wind-

ings on the secondary side, the primary windings being assumed to be all equal. Under this assumption, the turns or coils of each of the secondary windings ZY and WX should, as nearly as convenient, be divided at the point L and K into two portions in the proportion of about 7 to 17 as shown in Figs. 1 and 2, although in practice, for convenience of manufacture, these intermediate points may be otherwise distributed and rectifications made in the other windings, so as to effect the same results.

Now taking the figures given on the diagram Figs. 1 and 2, the pressure difference between electrode 1 and the neutral electrode N is equal to WK , plus MT reversed. In the vector diagram Fig. 3, this can be represented by the lines Oe and Od giving the resultant $O1$. Similarly the pressure difference between electrode 2 and the neutral electrode N can be represented by KX reversed, plus MT reversed. These are represented by the lines Oe and Od in Fig. 3, and give the resultant $O2$. Similarly we find the pressure difference between electrodes 3 and 4 and the neutral electrode N as the resultants $O3$ and $O4$ respectively. It will be seen that the system induces equal pressures between each of the electrodes and the neutral.

The lines $O1$, $O2$, $O3$ and $O4$ can be taken as representing the directions of the currents flowing in the four electrodes 1, 2, 3 and 4, so that if along each of these lines distances are marked off equal to the number of coils under their influence, the number of ampere-turns in each section of the winding can be obtained. Assuming that unit current is flowing through each of the electrodes 1, 2, 3 and 4, then along line $O1$ a distance Og can be marked off equal to 7 and along line $O2$ a distance Og can be marked off equal to 17. The vector difference fg of those two lines will give the ampere-turns in the primary winding CO . Similarly the ampere-turns in the primary winding BO can be found to be equal to hk .

Now the current in the secondary winding VT of the third transformer AO — VT is the vector difference between the vector sums of the currents in the secondary windings of the other two transformers. The current flowing from the point T to the point K is equal to the vector sum of the currents flowing to electrodes 1 and 2 and the current flowing from the point V to the point L is equal to the vector sum of the current flowing to electrodes 3 and 4. The difference between these vector sums is equal to the current flowing in VT and after taking into account the number of windings, the line np is obtained as representing the ampere-turns in the primary winding AO . It will be seen that the lines fg , hk and np are all equal, and as it has been assumed for clear-

ness that the primary windings have all the same number of turns, then the currents in the primary windings are all equal. Furthermore, by taking the vector sum of all the currents flowing through the electrodes 1, 2, 3 and 4, the line ON is obtained as representing a current which would flow through the neutral electrode N assuming that the length of the line Od represents the normal current in each electrode 1, 2, 3 and 4 and that the hearth is a good conductor.

As the lines $O1$, $O2$, $O3$ and $O4$ (Fig. 3) represent the respective directions of the currents passing through the electrodes and taking into account the number of windings under the influence of each current and the respective directions and magnitude of the currents, it will be found that when equal currents are taken through the arcs between the electrodes 1, 2, 3 and 4 and the metal in the furnace then equal currents are drawn from the three primary mains, and also that these currents are substantially in phase with their respective voltages, so that the power factor on a non-inductive load is high. Furthermore, when equal currents pass through the electrodes there is a balance or return current which is equal to or greater in amount than that in one of the phases.

Again, Fig. 3 shows that if the furnace bottom does not for any reason conduct the current to the return electrode N , then the currents in the primary mains will remain well balanced, and have on a non-inductive load, a power factor of practically unity.

Thus it will be seen from Fig. 3 that the hereinbefore described arrangement of transformer windings and electrodes when combined with an electric furnace enable the following features to be obtained, namely:

1. A four-phase current with a neutral return current in a direction at right angles to the directions of the current between the phases in the bath of metal, so as to satisfy metallurgical requirements.

2. That when equal E. M. F.'s are impressed by the primary windings, equal E. M. F.'s are induced between each of the four secondary windings and the neutral electrodes.

3. That when equal currents are taken through the four secondary windings to the electrode as well as a suitable current to the neutral return, equal currents are taken from the three primary windings.

4. That when unequal currents are flowing through the four secondary windings, due to defective electrode regulations, or resistance of the hearth, the three primary currents remain balanced to a permissible degree.

5. That the power factor of the system is high, since angular displacement of the E. M. F.'s and corresponding currents in the

primary windings and mains is small under working conditions.

It is to be understood that the above mentioned proportions of the three transformer ratios and the positions of the intermediate tapping points can be slightly modified without affecting the scope of the invention which includes such modifications.

Each of the electrodes 1, 2, 3 and 4 and 10 the neutral electrode N instead of consisting of a single electrode may be replaced by a group of two or more electrodes spaced apart.

What I claim is:—

15 1. A three phase transformer arrangement comprising three sets of primary and secondary windings, two of the sets of such windings being of the same transformer ratio and the other or third set being of different transformer ratio to the other two sets, the secondary system of the two sets of equal transformer ratio having four terminals and the secondary system of the third set being interconnected with the secondary systems of the other two sets, for the purpose specified.

20 2. A three phase transformer arrangement comprising three sets of primary and secondary windings, two of the sets of such windings being of the same transformer ratio and the other or third set being of greater transformer ratio to the other two sets, the secondary system of the two sets of equal transformer ratio having four terminals and the secondary system of the third set being interconnected with the secondary systems of the other two sets, for the purpose specified.

25 3. A three phase transformer arrangement comprising three sets of primary and secondary windings, two of the sets of such windings being of the same transformer ratio and the other or third set being of different transformer ratio to the other two sets, the secondary system of the two sets of equal transformer ratio having four terminals and the secondary system of the third set being interconnected with the secondary systems of the other two sets and connected 30 to a fifth terminal for the purpose specified.

40 4. A three phase transformer arrangement comprising three primary windings and three secondary windings magnetically associated therewith, the transformer ratio of two such pairs of associated windings being equal and the transformer ratio of the third pair of such windings different there-to, terminal connections from each end of the secondary windings of the two pairs of 45 windings of equal transformer ratio, connections from the ends of the third secondary winding to points intermediate of the remaining secondary windings and a terminal connection intermediate of the third secondary winding, for the purpose specified.

5. A three phase transformer arrangement comprising three primary windings and three secondary windings magnetically associated therewith, the transformer ratio of two such pairs of associated windings 50 being equal and the transformer ratio of the third pair of such windings of greater value than that of the two pairs of equal transformer ratio, terminal connections from each end of the secondary windings of the two pairs of windings of equal transformer ratio, connections from the ends of the third secondary winding to points intermediate of the remaining secondary windings and a terminal connection intermediate of the third secondary winding, for the purpose specified.

6. A three phase transformer arrangement comprising three primary windings and three secondary windings magnetically associated therewith, the transformer ratio of two such pairs of associated windings 55 being equal and the transformer ratio of the third pair of such windings of greater value than that of the two pairs of equal transformer ratio, terminal connections from each end of the secondary windings of the two pairs of windings of equal transformer ratio, connections from the ends of the third secondary winding to points intermediate of the remaining secondary windings and a terminal connection at the central point of the third secondary winding, for the purpose specified.

7. A three phase transformer arrangement comprising three primary windings and three secondary windings magnetically associated therewith, the transformer ratio of two such pairs of associated windings 60 being equal and the transformer ratio of the third pair of such windings of greater value than that of the two pairs of equal transformer ratio, terminal connections from each end of the secondary windings of the two pairs of windings of equal transformer ratio, connections from the ends of the third secondary winding to points of the remaining secondary windings dividing the latter each into two parts of unequal proportions, and a terminal connection intermediate of the third secondary winding, for the purpose specified.

8. A three phase transformer arrangement comprising three primary windings and three secondary windings magnetically associated therewith, the transformer ratio of two such pairs of associated windings 65 being equal and the transformer ratio of the third pair of such windings of greater value than that of the two pairs of equal transformer ratio, terminal connections from each end of the secondary windings of the two pairs of windings of equal transformer ratio, connections from the ends of the third secondary winding to points of 70 the third secondary winding, for the purpose specified.

the remaining secondary windings dividing the latter each into two parts of unequal proportions and a terminal connection at the central part of the third secondary winding, for the purpose specified.

9. A three phase transformer arrangement comprising three primary windings and three secondary windings magnetically associated therewith, the transformer ratio of two such pairs of associated windings being equal and the transformer ratio of the third pair of such windings being of about 20% greater value than that of the other two pairs of equal transformer ratio, terminal connections from each end of the secondary windings of the two pairs of windings of equal transformer ratio, connections from the ends of the third secondary winding to points of the remaining secondary windings dividing the latter each into two parts of unequal proportions and a terminal connection at the central part of the third secondary winding for the purpose specified.
10. A three phase transformer arrangement comprising three primary windings equal in value to one another, a pair of secondary windings also equal in value to one another and a third secondary winding of lesser value, terminal connections from each end of the pairs of secondary windings of equal value, connections between the ends of the secondary winding of lesser value and points intermediate of the other secondary windings and a terminal connection intermediate of the said secondary winding of lesser value, for the purpose specified.

11. A three phase transformer arrangement comprising three primary windings and three secondary windings magnetically associated therewith, the transformer ratio of two such pairs of associated windings being equal and the transformer ratio of the third pair of such windings of equal value to one another and a third secondary winding of lesser value, the proportions of turns in the primary winding associated with the latter winding to the number of turns in such secondary winding being in the proportions of about six to five, terminal connections from each end of the pair of secondary windings of equal value, connections between the ends of the secondary winding of lesser value and points intermediate of the other secondary windings, each point dividing each of such other secondary windings into two parts in the proportion of about seven to seventeen and a terminal connection at the central part of the third secondary winding for the purpose specified.
12. A three phase transformer arrangement comprising three primary windings equal in value to one another, a pair of secondary windings also equal in value to one another and a third secondary winding of lesser value, the proportions of turns in the primary winding associated with the latter winding to the number of turns in such secondary winding being in the proportions of about six to five, terminal connections from each end of the pair of secondary windings of equal value, connections between the ends of the secondary winding of lesser value and points intermediate of the other secondary windings, each point dividing each of such other secondary windings into two parts in the proportion of about seven to seventeen and a terminal connection at the central part of the third secondary winding for the purpose specified.

13. A three phase transformer arrangement comprising three primary windings equal in value to one another, a pair of secondary windings also equal in value to one another and a third secondary winding of lesser value, the proportions of turns in the primary winding associated with the latter winding to the number of turns in such secondary winding being in the proportions of about six to five, terminal connections from each end of the pair of secondary windings of equal value, connections between the ends of the secondary winding of lesser value and points intermediate of the other secondary windings, each point dividing each of such other secondary windings into two parts in the proportion of about seven to seventeen and a terminal connection at the central part of the third secondary winding for the purpose specified.

14. A three phase transformer arrangement comprising three primary windings equal in value to one another, a pair of secondary windings also equal in value to one another and a third secondary winding of lesser value, the proportions of turns in the primary winding associated with the latter winding to the number of turns in such secondary winding being in the proportions of about six to five, terminal connections from each end of the pair of secondary windings of equal value, connections between the ends of the secondary winding of lesser value and points intermediate of the other secondary windings, each point dividing each of such other secondary windings into two parts in the proportion of about seven to seventeen and a terminal connection at the central part of the third secondary winding for the purpose specified.

Signed at London, England, this eighth day of November, 1917.
